(57) **CLAIM**

The ornamental design for a fender flare, as shown and described.

DESCRIPTION

FIG. 1 is a front, right and top side perspective view of a fender flare showing my new design;

FIG. 2 is back, left and bottom side perspective view thereof;

FIG. 3 is a front and left side perspective view thereof;

FIG. 4 is a back and left side perspective view thereof;

FIG. 5 is a front elevation view thereof;

FIG. 6 is a back elevation view thereof;

FIG. 7 is a left side elevation view thereof;

FIG. 8 is a right side elevation view thereof;

FIG. 9 is a top plan view thereof;

FIG. 10 is a bottom plan view thereof; and,

FIG. 11 is an enlarged view of the encircled portion in FIG. 9.

The equal-length broken lines depict portions of the fender flare that form no part of the claimed design.

The dash-dot lines in FIG. 9 and FIG. 11 indicate the boundaries of the enlarged views and are used for annotative purpose only. They do not limit or define the scope of the claimed design.
